SHELLING MACHINE

Application filed September 20, 1929. Serial No. 394,061.

This invention relates to new and useful improvements in shelling machines and the object of the invention is to provide a simple and easily adjusted machine which will remove the husks from rice or the like without injuring the germ.

According to my invention, I take the rice in the paddy or husk and feed into a hopper which is positioned above a belt. This belt is grooved transversely and carries the rice towards and against a flexibly supported abrading surface which removes the husk and allows the grains of rice to be free therefrom. The belt is mounted so that its position and tension may be adjusted and the abrading surface may be moved towards or away from the belt. The flexible mounting of the abrading surface permits said surface to yield in case of an overfeed so as to prevent injury to the germ of the grain. Suitable driving mechanism is provided for operating the belt.

In the drawings which illustrate my invention,

Figure 1 is a side elevation of my improved shelling machine.

Figure 2 is a plan view of the machine shown in Figure 1.

Figure 3 is a perspective view of a part of the conveyor belt, by means of which the rice or grain is delivered to the abrading surface.

Figure 4 is an enlarged fragmentary perspective view showing the mounting of the abrading surface and its relation to the conveyor belt.

Figures 5 and 6 are views disclosing certain details of construction shown in Figure 4.

Figure 7 is a fragmentary side elevation of a modified type of shelling machine.

Referring more particularly to the drawings, 11 designates a frame supporting a hopper 12 equipped with a restricted outlet 13 positioned in proximity to an endless belt 14. The forward end of the belt is trained around and supported by a pair of pulleys 15 and 16 mounted in swinging frame 17. The opposite end of the belt is trained around and supported by a single pulley 18 mounted in a

swinging frame 19. The frame 19 comprises a pair of vertically inclined arms 20 having their lower ends pivoted to the frame members 21 as indicated at 22. The upper ends of said arms carry between them the shaft 22a on which the pulley 18 is mounted. Pivotally secured to each of said arms is one end of an adjusting bolt 23, the other end of which is passed through a transverse frame member 24 and equipped with a wing nut 25. It will be manifest that, through the agency of bolts 23 and nuts 25, the position of the frame 19, and pulley 18, may be adjusted to regulate the tension of belt 14.

The pulleys 15 and 16 are staggered as shown in Fig. 1, so that the portion of the belt passing downwardly from the pulley 15 to the pulley 16 provides a sloping surface 26 onto which is deposited the rice or grain discharged through the hopper outlet 13. The particular angle or slope of the belt portion 26 may be varied to advance or retard the feed of grain deposited thereon. To this end the side members 27 of the frame 17 are equipped with trunnions 28 journalled in the frame members 29 and equipped with clamping nuts 30 by means of which the frame 17 is held in any of the various angular positions to which it is adjusted.

The pulleys 15 and 16 are mounted on shafts 31 and are equipped with relatively large side flanges 32 serving to prevent lateral displacement of the grain delivered to the sloping belt portion 26. The pulley shafts 31 are equipped at one end with chain sprockets 33 meshing with a drive chain 34. Chain 34 is also trained around a sprocket 35 fixed to a shaft 36 journalled in a suitable swinging frame presenting side members 37 having their upper terminals pivoted to the top members of the frame 11, as indicated at 38. Shaft 36 also carries a pulley 39, which is connected by a belt 40 to the pulley 41 of an operating motor 42. Pivotally secured to the lower end of the arms 37 are a pair of adjusting bolts 43 the free ends of which pass outwardly through the vertical flange 44 of an angle bar 45 and are equipped with wing nuts 46. These bolts 43 and nuts 46 enable

the position of the arms 37 to be adjusted to maintain proper tensioning of the chain 34.

An abrading element 47 is positioned opposite the sloping belt portion 26 and in parallel relation thereto. The abrading element preferably comprises a suitable backing having the surface opposing the belt portion 26 covered with a suitable abrading material 48, as shown to advantage in Fig. 4. The upper end of element 47 is supported from the shaft 36 through the medium of a spring steel plate 49. One end of plate 49 is hinged to the element 47 as indicated at 50. The other end of plate 49 is provided with a slot 51 through which protrudes a threaded stud 52 carried by a sleeve 53 on the shaft 36. The stud 52 is equipped with a clamping nut 54 by means of which the plate 49 is secured in different positions of adjustment. The sleeve 53 may be provided with guide flanges 55 lying at opposite sides of the plate 49 and the portion of the sleeve carrying the stud 52 may be flattened as at 56 to provide a suitable slide bearing for said plate. The lower portion of the abrading element 47 is secured to the horizontal flange 57 of the angle bar 45 through the medium of flexible steel plates 58 and 59. The plate 58 is hinged at one end to the member 47 and is provided at the other end with a threaded stud 60 operating in a slot 61 formed in the overlapping end of the plate 59. A clamping nut 62 carried by the stud 60 enables the said plates to be secured together in different positions of adjustment. The outer end of plate 59 is bolted as at 63 to the aforesaid flange 57.

It will be evident that, through the agency of the particular supporting means herein described, the abrading element 47 may be adjusted towards or away from the sloping belt portion 26, so as to give any desired clearance. The aforesaid supporting means also enable the angular position of the abrading element to be varied to suit variations in the slope or inclination of the opposing belt portion 26.

In operation, rice in the paddy is supplied to the hopper and flows through the discharge orifice 13 onto the belt 14 preferably at a point above the pulley 15 and in close proximity to the upper end of the abrading element 47. The belt travels in the direction indicated by the arrow 64 and the abrading surface is adjusted so that the clearance between said surface and the opposing portion of the belt is sufficient to take care of the largest grains of rice being hulled. The belt carries the rice towards the abrading surface and the paddy or hull is removed from the larger grains. If any of the smaller grains of rice should not respond to this treatment, they are again placed in the hopper and the abrading surface shifted sufficiently closer to the belt to take care of such smaller grains. It has been found that the best results are

obtained by using a conveyor belt, the surface of which is provided with transversely extending grooves 65 having the walls thereof curved as clearly shown in Fig. 3. This particular type of belt allows the rice in the paddy to be pocketed in such a way that the husks are brought into engagement with the abrading material and removed without injuring the rice and the germ thereof. In case of an overfeed resulting in excessive accumulation of grain between the abrading surface and the opposing portion of the conveyor belt, injury to the grain and germ is prevented by reason of the fact that the abrading surface is capable of yielding due to the flexibility of its supporting plates.

In Fig. 7 I have shown a slight modification in which the abrading element is in the form of a pulley 66 having its surface covered with a suitable abrading material. This pulley is mounted in a swinging frame 67 and is adjustable towards or away from the belt 14a through the agency of adjusting bolts 68 connecting the lower end of the swinging frame to the members 11a of the main supporting frame 11b.

The drawings are only illustrative of two types of machines which may be used and it will be readily understood that various modifications may be made thereto without departing from the spirit of the invention.

Having thus described my invention, what I claim is:

1. A shelling machine comprising a supporting structure, a frame carried by the supporting structure and mounted for swinging adjustment about a horizontal axis, pulleys mounted in the upper and lower portions of said frame above and below said axis, means for securing said frame in various positions of vertical inclination with the upper and lower pulleys disposed in relatively staggered relation, an adjustably mounted return pulley, a substantially horizontal endless carrier trained over said pulleys, the portion of the carrier passing from the upper to the lower of the first mentioned pulleys being inclined by the staggered arrangement of said pulleys to present a sloping surface the angle of which is dependent upon the adjustment of the swinging frame carrying said pulleys, an abrading surface adjustably supported in parallel relation with the sloping surface of said carrier, means for adjusting the abrading surface in the direction of said sloping surface to vary the intervening clearance and means for varying the angular adjustment of said abrading surface to correspond with variations in the angular adjustment of the sloping surface of the carrier.

2. A shelling machine comprising a supporting structure, a frame carried by said structure and mounted for swinging adjustment about a horizontal axis, in order to permit said frame to be disposed in various po-

sitions of vertical inclination, means for securing said frame in adjusted position, a pair of pulleys mounted in the frame above and below the axis about which the frame is movable, a return pulley, an endless carrier trained over said pulleys so that a sloping surface is formed at one end of the carrier by reason of the staggered arrangement of the first mentioned pulleys due to vertical 5 inclination of the frame carrying said pulleys, an abrading member arranged with its abrading surface parallel with the sloping surface of said carrier, a supporting arm having one end pivoted to a portion of said 10 supporting structure and the other end hingedly connected to an upper portion of said abrading member and a lengthwise adjustable connection between the supporting structure and a lower portion of the abrading 15 member, said lengthwise adjustable connection being operable to adjust the working position of the abrading member.

20

In witness whereof, I have hereunto set
my hand.

25

ANDREW RANKINE.
